THE ATTORNEY

UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,012,928.

Specification of Letters Patent. Patented Dec. 26, 1911.

Application filed March 23, 1911. Serial No. 616,318.

To all whom it may concern:

Be it known that I, HERBERT H. STEELE, a citizen of the United States, and resident of Marcellus, in the county of Onondaga and 5 State of New York, have invented certain new and useful Improvements in Type-Writing Machines, of which the following is a specification.

My invention relates to typewriting machines and more particularly to means whereby tabulating operations may be automatically effected as the writing proceeds, and without the exercise of any care or judgment on the part of the operator, and 15 without the actuation of special tabulating keys.

To the above and other ends which will hereinafter appear, my invention consists in the features of construction, arrangements of parts and combinations of devices 20 to be set forth in the following specification and particularly pointed out in the appended claims.

In the accompanying drawings, wherein 25 like reference characters indicate corresponding parts in the various views, Figure 1 is a fragmentary vertical sectional view of the upper portion of the typewriting machine embodying my invention. Fig. 2 is a fragmentary rear elevation with parts in section of a portion of the mechanism disclosed in Fig. 1. Figs. 3, 4 and 5 are fragmentary rear elevations of the feed rack and pinion with the disengaging devices mounted 30 on the feed rack; the different views representing the parts as they are disposed at different points in the travel of the carriage. Fig. 6 is a fragmentary rear elevation of the feed rack with the modified form of disengaging device applied thereto. Fig. 7 is a 40 transverse sectional view of the same.

I have illustrated my invention in the present instance embodied in a Monarch typewriting machine, only so much of said 45 machine being shown as is necessary to illustrate my invention in its embodiment therein.

The top plate 1 of the machine has brackets 2 mounted thereon and these brackets 50 support oppositely grooved fixed guide rails 3 and 4. The carriage comprises a slide bar 5 provided with oppositely grooved guide rails 6 at the top and bottom edges thereof. Anti-friction balls or rollers 7 are interposed 55 between the fixed guide rails and the guide

rails 6 on the carriage bar 5. End bars or projecting brackets 8 extend forwardly from the slide bar 5 at the ends thereof and support a platen shaft 9 on which a cylindrical platen 10 is mounted. The carriage is 60 propelled by the usual spring drum 11 connected to the carriage by a strap or band 12, which latter is connected at one end to the drum and at its opposite end to a depending pin 13 on the carriage. The carriage is thus 65 mounted for movement across the top plate from side to side of the machine and is under control of the usual step-by-step letter feed or escapement mechanism. In the present instance this escapement mechanism comprises arms 14 pivoted to the carriage at 15 and connected at their rear ends to a feed rack 16. This feed rack meshes with a feed pinion 17 fixed to the forward end of a shaft 18 mounted to turn in a bearing supported 75 on a bracket 19 secured to the top plate of the machine. The rear end of this shaft is operatively connected to an escapement wheel 20 by the usual pawl and ratchet mechanism contained within a drum 21. Feed 80 dogs 22 and 23 are carried by a dog rocker 24 controlled in the usual manner by the finger keys; the dogs co-operating with the escapement wheel to afford a step-by-step movement of the carriage during the printing operations. A carriage scale 25 is mounted in the usual manner adjacent to the platen.

The parts thus far described are or may be of the usual construction employed in the Monarch machine. However, I prefer in 90 the present instance to provide the feed rack 16 with a scale on the rear side thereof, the scale comprising numerical indices 26 spaced apart to correspond to the spacing on the carriage scale for purposes which 95 will hereinafter more clearly appear.

The upper edge of the feed rack is preferably provided with recesses or indentures 27 each arranged opposite a space 28 between two adjacent teeth 29 on the feed rack. 100 I have provided a series of disengaging or closing devices each represented as a whole by the reference numeral 30. These devices as illustrated in Figs. 1, 2, 3, 4 and 5 are each made of a strip of wire bent on itself 105 to form a finger piece or projection 31, an engaging member 32 on one end, and a second engaging member 33 at the other end. The engaging member 32 is adapted to be seated in a recess 27 in the upper edge of 110

the feed rack, whereas, the lower engaging member 33 is adapted to be received in a space 28 between two adjacent teeth of the feed rack, which space is diametrically opposite the depression 27 in which the upper end of the disengaging device is received. There is sufficient resiliency between the two engaging members or arms 32 and 33 to cause them to spring slightly toward each other and then prevent the disengaging device from being accidentally displaced rearwardly from the feed rack. Each of the devices 30, however, may be detached from the rack and adjusted along it to different set positions. It will be understood that the scale on the back of the feed rack facilitates an adjustment of the disengaging devices along the rack, and with reference to different positions indicated on the carriage scale. The disengaging devices in the present instance are such that each of them is adapted to close a single space between two adjacent teeth 29 of the feed rack, and the closing in the present instance is effected by the member 33, being received in one of the spaces 28 on the rack and substantially filling said space as indicated in the drawings. In this manner the space is closed against the admission of the teeth of the feed pinion 30 therein. The effect of this construction is to temporarily bring about a disengagement between the feed rack and pinion during the letter-space feed of the carriage, and to afford a skipping movement of the carriage until the disengaging device passes to a point where it is no longer effective to maintain a disengagement between the rack and pinion. Then the feed rack drops down and reengages the pinion after a predetermined extent of skipping movement of the carriage has taken place. This will be clearly understood from a comparison of Figs. 3, 4 and 5. Fig. 3 illustrates the parts as they appear at the instant when an engaging device 30 is brought into coöperation with the feed pinion. Thus, it will be seen that as the carriage and feed rack move in the direction of the arrow under a step-by-step feed movement of the escapement mechanism, the part 33 of the engaging device 30 will be brought into contact with the tooth *a* on the feed pinion 17. At the next actuation of a finger key the feed pinion 17 will be rotated in the direction of the arrow from the position shown in Fig. 3 to that indicated in Fig. 4. This movement is effective to raise the rack against the weight thereof and the usual spring (not shown) employed to depress it, thereby disengaging the rack from the teeth 29 of the feed pinion. The carriage spring is then effective to move the carriage and rack in the direction of the arrow until the engaging device 30 has passed over the tooth *b* of the feed pinion, and the feed rack may then be depressed to effect a reengagement

with the teeth *a*, *b*, of the feed pinion. This skipping movement of the carriage is effective to move the tooth *d* of the feed rack from the position shown in Fig. 4 to that indicated in Fig. 5 and to bring the tooth *e* of the feed rack into engagement with the tooth *b* of the feed pinion as illustrated in Fig. 5. In other words, the free movement of the carriage effected by the disengagement described, in the present instance corresponds to two letter spaces of the carriage, or to the distance of two teeth of the feed rack; although the extent of this free skipping movement of the carriage may vary according to the character of the teeth on the feed rack and pinion.

In the present instance the engaging devices are provided to close but a single space 28 in the feed rack, although the number of spaces that may be closed by each of the disengaging devices may be varied at will. However, by employing a closing device for a single space 28 as a unit, this may be multiplied at will by adjusting the closing devices adjacent to one another. If, for instance, it is desired to afford a three letter-space skipping movement of the carriage, two of the disengaging devices 30 may be employed in adjacent rack spaces 28, and so on.

In Figs. 6 and 7 I have illustrated a modified form of disengaging or closing device preferably struck up from spring sheet metal and comprising a body portion 34, an engaging arm 35 terminating in a slight bend 36 and an angular portion 37 formed on a second arm 38 at the lower end of the strip 34; the said arm 38 and the angular portion 37 being received in the space 28 of the feed rack and closing the same against the admission of the teeth of the feed pinion.

In order that a clear understanding of the use of the automatically operating tabulating mechanism may be arrived at it may be assumed, for example, that a work sheet or blank, in the nature of a freight or way bill, is to be filled in and that such work sheet is ruled throughout the width thereof to divide the sheet in various vertical columns, each of which has printed headings or inscriptions. This work sheet is placed in the machine and an inspection of the carriage scale indicates the positions in the travel of the carriage where the various columns are divided. In the present instance it may be assumed that the distance from the last character inscribed in one column to the first character to be inscribed in the next column is a distance of two letter spaces; and this distance maintains between the columns throughout the sheet. In work sheets of this character the number of characters contained in each column is generally the same, so that the operator proceeds to write, say, four characters on the machine under the first heading. After the last character in

this column is written the carriage will automatically skip to bring the next column to a position where the first letter in said column may be written. After this is completed the carriage will automatically skip to the next column where the first character under the heading of that column may be written and so on through each successive column. It will be understood that the operator thus proceeds in the ordinary manner to fill in the items in the respective columns and that the carriage is automatically moved from column to column without actuating the special tabulating key or keys, and without the exercise of any special precaution to determine the columnar position of the sheet, this latter being automatically taken care of as the work proceeds.

It will be seen therefore that I have provided simple and efficient means for filling an tabulated reports, freight, or way bills and the like and by which much time and annoyance may be saved the operator. Moreover, it will be understood that the effect may be accomplished by the simple employment of the disengaging devices on existing styles of typewriting machines, such as the Monarch machine, without changing or materially changing the physical characteristics of said machines as they now exist. It will also be observed that the disengaging devices may be adjusted to various positions to operate at any point on the line of travel of the carriage and may be multiplied at any given point in order to increase the number of spaces desired for the free travel of the carriage between columns. It will be seen that in each of the forms shown the disengaging device constitutes means for closing certain of the spaces of the rack against the admission therein of the carriage feed device which co-operates with the feed rack and which, in the present instance, is the feed pinion.

While I have described one form of typewriting machine embodying my invention, it should be understood that various changes may be made without departing from the spirit and scope of my invention. Thus, from certain aspects of my invention I contemplate covering broadly the provision of means closing the spaces between certain teeth of the feed rack to provide an automatic tabulating operation. Moreover, certain of the claims of the present case are intended to cover a construction such as that embodied in my companion application, Serial No. 616,319 filed of even date herewith. In said companion application the claims are restricted to features not disclosed herein.

What I claim as new and desire to secure by Letters Patent, is:—

1. In a typewriting machine, the combination of a power driven carriage; escape-

ment mechanism therefor including a feed rack; and means for closing the space between certain of the teeth of said rack.

2. In a typewriting machine, the combination of a power-driven carriage; escapement mechanism therefor including a feed rack; and adjustable means for closing the space between certain of the teeth of said rack, the adjustment of said means determining which of said spaces shall be closed.

3. In a typewriting machine, the combination of a power-driven carriage; escapement mechanism therefor including a feed rack; and a plurality of independently adjustable devices for closing the spaces between certain of the teeth of said rack.

4. In a typewriting machine, the combination of a power-driven carriage; escapement mechanism therefor including a feed rack; and means for closing the space between certain teeth of the feed rack, said closing means being movable to an inoperative position.

5. In a typewriting machine, the combination of a power-driven carriage; escapement mechanism therefor including a feed rack; and a device for closing the space between certain teeth of said rack, said device being detachable from the machine.

6. In a typewriting machine, the combination of a power-driven carriage; escapement mechanism therefor including a feed rack; and a plurality of independently adjustable devices for closing the spaces between certain of the teeth of said rack, each of said devices being detachable from the rack and capable of closing the single space between an adjacent pair of teeth.

7. In a typewriting machine, the combination of a power-driven carriage; escapement mechanism therefor including a feed pinion and a feed rack mounted for movement into and out of engagement with said feed pinion; and independently adjustable devices for closing the spaces between certain of said teeth to automatically effect a disengagement between the rack and pinion when said devices reach the feed pinion and for automatically reestablishing engagement between the rack and pinion when said devices pass the pinion.

8. In a typewriting machine, the combination of a power-driven carriage; escapement mechanism therefor including a feed pinion, and a feed rack mounted for movement into and out of engagement with said feed pinion; and independently adjustable devices for closing the spaces between certain of said teeth, each of said devices closing the space between a pair of adjacent teeth on the rack.

9. In a typewriting machine, the combination of a power-driven carriage; escapement mechanism therefor including a feed

rack having a scale thereon corresponding to the carriage scale; and a device which is adapted to close the space between teeth on said rack and which may be adjusted to different positions along said rack and with reference to the scale thereon.

10. In a typewriting machine, the combination of a power-driven carriage; escapement mechanism therefor including a feed rack having a scale thereon corresponding to the carriage scale; and a feed pinion; and a device carried by said rack and adjustable thereon with reference to the scale on the rack, said device coöperating with said feed pinion to effect a disengagement between the rack and pinion.

11. In a typewriting machine, the combination of a power-driven carriage; escapement mechanism therefor comprising a feed rack and a coöperative feed device; and a disengaging device carried by said feed rack and operative to automatically disengage the rack from its coöperative feed device at a predetermined point in the travel of the carriage.

12. In a typewriting machine, the combination of a power-driven carriage; escapement mechanism therefor comprising a feed rack and a coöperative feed device; a disengaging device carried by said feed rack and operative to automatically disengage the rack from its coöperative feed device at a predetermined point in the travel of the carriage; and means by which an adjustment of said disengaging device may be effected to different points along said rack to determine at what point in the travel of the carriage the disengagement between the rack and its coöperative feed device shall take place.

13. In a typewriting machine, the combination of a power-driven carriage; escapement mechanism therefor including a feed rack and a coöperative feed device; and a disengaging device which is received at one end between teeth of the rack to prevent an adjacent rack tooth from engaging its coöperative feed device and which engages at its opposite end with the other edge of the rack, whereby said disengaging device may be detached from the rack and adjusted to different positions along the length there-

of and may be held against accidental displacement in any of the positions to which said disengaging device may be adjusted.

14. In a typewriting machine, the combination of a power-driven carriage; escapement mechanism therefor including a feed rack and a coöperative feed pinion; and a wire disengaging device which is received at one end between two adjacent teeth of the rack to prevent an adjacent rack tooth from engaging the feed pinion and to bring about an automatic disengagement between the feed rack and pinion to afford a free travel of the carriage in the direction of its feed, said device engaging at its opposite end with the other edge of the rack, whereby said disengaging device may be detached from the rack and adjusted to different positions along the length thereof and may be held against accidental displacement in any of the positions to which said disengaging device may be adjusted.

15. In a typewriting machine, the combination of a power driven carriage; escapement mechanism therefor including a feed rack, recesses therein on the edge of the rack opposite that which carries the teeth, each of said recesses being opposite a space between two adjacent teeth of the feed rack; and a disengaging device detachably connected to said feed rack and having a part which is received and substantially fills the space between two adjacent teeth on the rack and which is also received in the recess opposite said last mentioned space.

16. In a typewriting machine, the combination of a power driven carriage; escapement mechanism therefor including a feed rack and a coöperative feed device; and automatically operating means for effecting a disengagement between said feed rack and its coöperative feed device during the feed of the carriage, said means including a device carried by and detachable from said feed rack.

Signed at Syracuse, in the county of Onondaga, and State of New York, this 20th day of March, A. D. 1911.
